S. MACOMBER

CONNECTING MEANS FOR STRUCTURAL MEMBERS

Filed Jan. 6, 1926

FIG. 1.

FIG. 2.

FIG. 4.

FIG. 3.

INVENTOR
STANLEY MACOMBER
BY
George W. Saywell
ATTORNEY

UNITED STATES PATENT OFFICE.

STANLEY MACOMBER, OF MASSILLON, OHIO.

CONNECTING MEANS FOR STRUCTURAL MEMBERS.

Application filed January 6, 1926. Serial No. 79,530.

My invention relates to fire-proof floor construction and particularly to that part of said construction relating to the securing of expanded metal to the main support of the floor. The invention is designed to furnish means for effecting the locking together of these elements in an economical and efficient manner.

The annexed drawing and the following description set forth in detail certain means embodying my invention, such means constituting, however, but one of the various forms in which the principle of the invention may be embodied.

15 In said annexed drawing:

Figure 1 represents a plan view of a fragmentary portion of a structural assembly forming part of a fireproof floor construction, and illustrating my invention;

20 Figure 2 is a side elevation of the elements shown in Figure 1;

25 Figure 3 is a transverse vertical section, upon an enlarged scale, taken in the plane indicated by the line III—III, Figure 2; and

Figure 4 is a view similar to Figure 3 before the member locking the expanded metal to the support has been driven into place.

30 Referring to the annexed drawing in which the same elements are denoted by the same respective ordinals in the several views, I illustrate a main fireproof floor support by the ordinal 1, the same being any conventional form of joist or other main support provided it is formed with two spaced members, preferably upper members, between which a resilient wedge may be secured with a driving fit, as hereinafter fully explained.

40 The support 1 which is herein shown is a fragmentary section of a structural unit forming the subject matter of other patent applications filed by me and is provided with an upper chord member comprising two spaced bars 2—2. In ordinary fire-proof floor construction, the floor is provided with lath or expanded metal securely tied to the underlying support 1 and the same is illustrated herein by the ordinal 3.

45 The object of my invention is to provide an improved assembly for locking the lath 3 to the support 1. I do this by means of driving, at suitably spaced intervals, wedge-

shaped resilient members 4 through the lath 3 and into the space between the members 2. The member 4 is a wood block of about the shape shown in the accompanying drawing and preferably of a width greater than the mesh of the expanded metal 3, so that when the resilient block is driven through the metal 3, it distorts or possibly breaks the wires of the same and forces the distorted or broken wire sections downwardly against the opposed faces of the spaced bars 2 and locks these wires against said bar faces, all as plainly shown in Figure 3.

In a co-pending application filed concurrent date herewith, I have illustrated a use of the wedge 4 as a means for fastening an improved screed clip for supporting wood-floor nailing-strips, as well as for securing the expanded metal to the underlying joist support.

The advantage of the structural assembly 75 described is that thereby the lath is very quickly locked to the main support, it being necessary for the workman only to move rapidly along the joist, hammering in quickly at the desired spacing a series of wedges 80 4. The time consumed is not comparable to that necessitated in the common practice of fastening the lath 3 to the main support 1 by wire ties. Also, the connection is made very positively, and the wedge contributes 85 toward the tieing of the joist 1, or other support, to the concrete sub-base of the floor which is formed upon the top and around the lath 3, as is well understood by those skilled in the art.

90 What I claim is:

1. A structural assembly, in fire-proof floor construction, comprising the combination of expanded metal, a main support adjacently below said metal and formed with upper 95 horizontally-aligned spaced members, and means for securing the metal to the support comprising a wedge-shaped member of a width greater than the mesh of the expanded metal and intersecting the metal and fastened with a driving fit to and between the spaced members of the support.

2. A structural assembly, in fire-proof floor construction, comprising the combination of expanded metal, a main support adjacently below said metal and formed with spaced members, and means for securing the metal to the support comprising a wedge-

shaped resilient member of a width greater than the mesh of the expanded metal and intersecting the metal and driving fit to and between the spaced members of the support, the distorted and broken edges of the metal being forced downwardly and securely locked between the respective opposed faces of said spaced members and the adjacent sides of said wedge member.

Signed by me this 1st day of December, 1925.

STANLEY MACOMBER.
